[57] CLAIM

The ornamental design for a display package, as shown and described.

DESCRIPTION

FIG. 1 is a perspective view of a display package showing
my new design;

FIG. 2 is a top plan view thereof;

FIG. 3 is a bottom plan view thereof;

FIG. 4 is a left side elevation thereof; the right side elevation being a mirror image thereof; and

FIG. 5 is a front elevation thereof; the rear elevation being a mirror image thereof.

FIG. 1

FIG. 4

FIG. 5

FIG. 3

FIG. 2
